UNITED STATES PATENT OFFICE

LEWIS BRANDT, OF PITTSBURGH, PENNSYLVANIA, ASSIGNOR TO PITTSBURGH STEEL COMPANY, OF PITTSBURGH, PENNSYLVANIA, A CORPORATION OF PENNSYLVANIA

BUILDING STRUCTURE

Application filed October 8, 1928. Serial No. 311,008.

My invention relates to building structures and the method of making the same, and especially to floors, ceilings, and walls of buildings, etc., although it will be hereinafter described as applied more particularly to floor structures.

My invention has for one of its objects the provision of an improved manner of assembling concrete reinforcement and the sleepers 10 for floors, or studding for walls, etc., preparatory to application of concrete or other plastic material.

Another object of my invention is to provide an improved means for supporting concrete reinforcement.

Still another object of my invention is to provide an improved means for supporting floor sleepers against displacement during application of concrete in conjunction therewith and to accurately and positively maintain them in permanent position.

One form which my invention may take is shown in the accompanying drawings, wherein Figure 1 is a perspective view of a floor structure, with parts thereof broken away; Fig. 2 is a cross sectional view of the structure of Fig. 1; Fig. 3 is a cross sectional view thereof taken at right angles to Fig. 2; Fig. 4 is a side elevational view of one of the 30 chairs or sleeper supports of Figs. 1 and 3, on an enlarged scale, Fig. 5 is an end elevational view of the chair, and Fig. 6 is a perspective view of one of the hangers or stays for supporting the reinforcement.

Briefly, I show the floor structure as comprising a series of I-beams 7, paper back reinforcement 8, sleepers 9, concrete or plastic material 10, and flooring boards 11. The beams 7 need not necessarily be I-beams, but 40 beams or supports of any other form could be employed in lieu thereof. The fabric structure 8 is shown as composed of wire mesh in the form of strand and stay wires 12 to which a backing sheet 13 is secured by thread wires 14 which are disposed mainly to the underside of the sheet 13, but at intervals extend upwardly over certain of the wires 12, as shown more clearly in Fig. 3, and as described for example in the Benedict Patent 45 No. 1,597,507. However, reinforcement of

various other forms can obviously be employed.

In constructing the floor, the fabric sheet is placed upon the beams 7 and the sleepers 9 are supported in spaced relation thereto by 55 means of chairs 15.

The chairs 15 have downwardly-extending pointed wings or tongues 16 which may be pushed through the paper and bent around the upper flanges of the I-beams 7, as shown in Fig. 2. The upwardly-extending wing portions lie against the sides of the sleepers and may be fastened thereto by nails driven through holes 17. Holes 18 are provided for the reception of aligning pins in those cases 60 where the fabric sheet and the chairs are first placed in position upon the beams, and the sleepers then assembled therewith. In such case, the aligning pins will insure that the sleepers will have proper vertical positions 65 and nails will be driven through holes 17 after the sleepers are in place.

If desired, the chairs and the sleepers may be assembled previously to placing the same upon the beams, by driving nails through 75 the holes 17, the holes 18 serving in that case also as means for aligning the sleepers. The fabric also can be assembled with the chairs by inserting the tongues 16 therethrough and bending them, and the parts thus assembled 80 placed in position upon the beams. Hangers or stays 19 of yoke-like form extend over the sleepers, and their lower hooked ends are caused to engage one of the wires 12 to prevent sagging of the fabric sheet at points 85 between the beams. If desired, the hangers may be somewhat shorter than shown so that those portions of the sheet between the beams will be elevated, and thus result in an arched effect for the concrete, with a resulting increase in strength of structure.

After the fabric sheet and the sleepers have been installed, concrete is poured to form slabs 21 which may be in effect a continuous slab. The paper 13 serves as a form or support for 95 the concrete until it becomes hard, while the wires 12 will be imbedded therein and reinforce the same. If the space between the sheet 13 and the top plane of the sleepers is only partially filled, there will be space for 100

conduits, sound-proofing material, etc., between the upper surface of the concrete and the flooring boards 11.

As shown more clearly in Fig. 3, portions 5 22 of concrete will flow between the upstanding wings of the chairs 15, thus more rigidly holding the chairs in the concrete slab and preventing vertical displacement thereof, with the advantage that all of the sleepers 9 10 will be rigidly supported against vertical movement and a true floor level maintained, with no vertical play of the sleepers and the flooring boards which are secured to the sleepers.

15 While certain of the appended claims refer to the use of concrete and to the invention as applied to a floor structure, it will be understood that I use the word concrete in its broad sense to include various kinds of plastic material and that the invention in certain 20 of its aspects is applicable also to walls and ceilings.

I claim as my invention:—

Building structure comprising sleepers, 25 floor beams, reinforcing fabric composed of a wire mesh backed by a paper form sheet disposed against said beams and extending across the spaces between adjacent beams, and sheet metal chairs each having a flat body 30 portion straddling said beams and downwardly-extending pointed wing portions to permit them to be forced through the paper backing and bent around the flanges of the floor beams and having upwardly-extending 35 side portions affording vertical and lateral support to the sleepers in vertically spaced relation to the said beams.

In testimony whereof I, the said LEWIS BRANDT, have hereunto set my hand.

LEWIS BRANDT.
